SUCTION GOVERNOR

Raymond Hufford, Anderson, Ind.

Application October 22, 1938, Serial No. 236,395

20 Claims. (Cl. 137—152)

This invention relates to an automatic governor for controlling the speed of an internal combustion engine by controlling the fuel supply thereto.

The chief object of this invention is to provide a flexible and foolproof automatic governor adapted to control the speed of an internal combustion engine by controlling the fuel supply thereto.

The chief feature of the invention consists in providing a governor structure capable of accomplishing the foregoing object.

Another object of the invention is to provide a governor structure which can be adjusted over a long range of engine speeds without sacrificing engine performance at any governed speed.

Another feature of the invention is the arrangement of the operative parts of the governor such that if an attempt be made to render the governor inoperative in the customary manner heretofore employed with previous governors, said attempt will be not only fruitless but will on the contrary reduce the maximum governed speed.

One outstanding characteristic of the present invention as distinguished from previous governor structures of velocity type, is the inclusion of a stem or plunger which opposes the closing movement of the fuel control valve. This is the reverse of the usual governor practice. It is an arrangement that makes the instant invention tamper-proof.

The invention herein disclosed is illustrated as of two basic embodiments and one of these embodiments is illustrated in two sub-generic forms.

Other objects and features of the invention will be set forth more fully hereinafter.

The full nature of the invention will be understood from the accompanying drawings and the following description and claims:

In the drawings, Fig. 1 is a side elevational view of a governor embodied as an adaptor for inclusion in the fuel supply to an internal combustion engine, the cover being removed.

Fig. 2 is a top plan view thereof, a portion of the casing being broken away to show other parts in detail.

Fig. 3 is an end elevation of the governor shown in Figs. 1 and 2 and looking toward the right in said figures.

Fig. 4 is a view similar to Fig. 1 and of a slightly more modified form of the invention.

Fig. 5 is a view similar to Fig. 2 and of the same form of the invention shown in Fig. 4.

Fig. 6 is a view similar to Fig. 4 and of the

same form of the invention but showing the parts in another operative position.

Fig. 7 is a view similar to Fig. 3 and of the form of the invention shown in Figs. 4 to 6.

Fig. 8 is a sectional view taken on line 8—8 of Fig. 7 and in the direction of the arrows.

Fig. 9 is a sectional view taken on line 9—9 of Fig. 5 and in the direction of the arrows.

Fig. 10 is a view similar to Figs. 2 and 5 and of a second basic form of the invention, parts of the casing being broken away to show other parts in detail.

Fig. 11 is a side elevational view of the invention shown in Fig. 10, the cover portion being omitted.

Fig. 12 is a view similar to Fig. 11 but showing the parts in another operative position, the disclosures in Figs. 11 and 12 corresponding respectively to the disclosures in Figs. 6 and 4, respectively.

Fig. 13 is a chart of valve position plotted against opposed force or torque of the invention with the cam adjusted for 1500, 2000 and 2500 R. P. M. control.

Fig. 14 is a chart of valve position plotted against vacuum in inches for an engine held to 1500, 2000 and 2500 R. P. M.

Fig. 15 is a chart similar to Fig. 13 of prior art devices wherein the cam is non-adjustable.

Fig. 16 is a plan view of an anti-friction type lever and link structure similar to that illustrated in Figs. 1, 4 and 6.

Fig. 17 is an elevational view of same similar to that disclosed in Figs. 2 and 5.

Fig. 18 is similar thereto but taken at right angles to Fig. 17.

Fig. 19 is an enlarged central sectional view through one of the anti-friction constructions.

In Figs. 1 to 3 of the drawings, 10 indicates a tubular portion that terminates at opposite ends in outwardly directed flanges 11 connected by the web portions 12 provided with the bores 13 therein. This arrangement is provided so that the governor structure may be interposed between the carburetor and the intake and thus subject to engine suction and fuel velocity.

In offcenter or eccentric relation and extending across the passage 10a through the tubular portion 10 is a shaft 14 which suitably supports as at 15 an elliptical valve 16. This valve is so mounted that the long end thereof is on the upstream side of the shaft axis so that the valve is responsive to the downstream flow of the fuel mixture. Such a valve is known as an unbalanced valve. The shaft at one end is suitably

supported in an anti-friction structure indicated by the numeral 17, mounted in a boss 18. The other end of the valve shaft 14 is similarly supported as at 19 in a boss structure 20 that terminates in a plate portion 21. The plate portion 21 is provided with a side wall arrangement indicated generally by the numeral 22 to form a chamber 29 and the face of said wall is tapped and threaded as at 23 for cover mounting.

Suitably secured to one end of the wall 22 and to the boss portion 20 as by an integral formation is a housing structure 24 provided with a cap 25 at its outer end and suitably secured thereto as at 26. Reference will be had more fully hereinafter to the mechanism and arrangement of parts within the structure 24.

The plate portion 21 is suitably apertured as at 27 and 28 and mounted within the chamber 29 are the members 30 and 31 which are tapped and threaded, said members being secured in the openings 27 and 28, respectively.

Projecting outwardly from the side wall opposite the portion 24, is the portion 32. The side wall is threaded as at 33 and an adjusting screw 34 is mounted in said threaded aperture and the head portion thereof is nested within the chamber 35 formed in the portion 32.

An adjusting screw 36 suitably secures an arm structure 37 to the support 38. An adjusting screw 38 suitably secures a structure 39 to the support 31. The structure 39 has a bearing portion 40 of any conventional form. It bears on the head 31a of the arm 37. The member 39 after once being adjusted, is a stationary element insofar as governor subsequent use and operation is concerned.

Arm 37 is adjusted to the desired position by means of the bolt 34. The opposite end of the arm is apertured as at 37b and has anchored to it one end of a spring 41, the other end of which is suitably anchored to a pin 42 carried by a pair of spaced links 43. These links 43 also carry a pivot 44 which mounts a roller 45 between the links and this roller is adapted to engage the portion, face or surface 46 of desired conformation by reason of the constraint imposed by the spring 41.

The shape of the portion 46 is determined by the amount of spring resistance required from spring 41 to balance the turning effort of the valve 16 less the amount of the opposing effort of the power piston operatively associated therewith, as hereinafter set forth. Generally this surface 46 is shaped to change the direction of travel of the link structure 43 as the arm 47 through the roller 45 is tilted and this action accelerates the extension of the spring 41 the desired and predetermined amount, determinable by the formation of the surface 46. As illustrated the effective surface 46 is of modified sine character and hence is termed "sinusoidal surface."

The two links 43 straddle the arm 47 rigid with the end of the shaft 14 exposed within the chamber 29. These links are secured to said arm as at 48. The arm 47 on the face remote from the plate 21 mounts a pivot 49 in turn supporting a roller 50.

It will be understood the surface 31a of the arm 37 may be of any desired conformation, likewise portion 40. Adjustment of the bolt 34 thus simultaneously adjusts the position of the cam 39 and the effective anchor point for the end of the spring 41 and, therefore, the tension of said spring. The arrangement of the parts is such

that the governor may be adjusted so that it may be said to maintain any predetermined speed from, for example, 1,500 R. P. M. to 3,000 R. P. M. and give very satisfactory performance through this entire range and naturally, of course, give satisfactory performance at the set speed within that range. After this adjustment is effected, the retaining screws 36 and 38 are tightened down to maintain cam 39 and arm 37 stationary.

It will be obvious, of course, in place of the single adjustment herein illustrated or its equivalent, individual adjustments for the arm 37 and the sinusoidal faced member 39 may be provided without departing from the broader features of the invention.

There is formed within the body extension 24 a cylinder 51 in which is mounted a piston 52, the stem 53 of which constitutes a plunger. This stem has its end slidably supported in the aperture 53a formed in the wall 22 of the casing of the chamber 29. It is juxtaposed relative to the roller 50 and is normally conditioned for roller contact during operation.

The piston 52 includes a peripheral skirt portion 54 and encircling the plunger stem is a coil spring 55, the piston bearing end thereof being seated within the skirt portion, the opposite end thereof bearing against the wall 51a at the opposite end of the cylinder and which is also apertured, the same being a continuation of the aperture 53a. As shown in Figs. 1 and 2, the wall 51a may have an externally threaded sleeve so that the force of the spring 55 may be adjusted to that desired or required.

An extension 56 on the piston constitutes a stop. If desired the end thereof may support a cushion member 57 for cushioning cap contact. This eliminates noise and that would be the sole purpose of such an addition. The extension 56, however, does normally space the piston from the cap 25 when the piston is in its extreme right hand position. This forms a chamber on the right hand side of the piston with which the passage 58 communicates. Another passage 59 is an extension and communicates as at 60 with the fuel passage 10a—see Fig. 1—the passages and ports 58, 59 and 60 constituting the power piston venting arrangement.

Also formed in the passage 10a—see Fig. 1—50 is a vent or port 61 which leads into the chamber 29 and the same communicates by passage 62—see Fig. 1 and Fig. 3—that opens upon the left hand wall of the cylinder 51 and thereby subjects the piston 52 to the force of vacuum below the valve 16. Chamber 29 is provided with a cover 63 and is sealed by gasket 29a and the same are secured to the face of the side walls 22 by screws 63a or the like. The resulting construction is such that one end of the piston is subjected to the pressure through conduit 10a of the downstream side of the valve 16 by means of the vacuum arrangement 61—29—62.

The amount of resisting effort desired to oppose the turning effort of the valve 16 through the lever 47 and roller 50 by the said piston 52 or rather the plunger portion thereof, can be controlled by the area of the piston and the rate of the power spring 55 opposing the effort of the piston 52. The outer end of the power piston 52 is subjected to the pressure on the upstream side of the valve 16 through the passage arrangement 58—59—60.

Piston 52 is controlled entirely by the pressure within the conduit 10a. One end is subjected to the pressure on the downstream side of the gov-

ernor valve 16 through port 60 leading into housing 29, and the other end is subjected to the pressure on the up-stream side of the valve 16. When the carburetor throttle is wide open, this pressure will vary from approximately 2" vacuum in Hg to 2.5" Hg while the pressure on the downstream side of valve 16 will vary from approximately 5" Hg to 20" vacuum in Hg. It is this differential of pressures that piston 52 is subjected to that assists in balancing the effort or torque on the valve 16, when the governor is in control of the engine and the carburetor throttle valve is wide open.

However, when the carburetor valve is moved towards a closed position, the pressure on both sides of the valve 16 becomes more evenly balanced, thus rendering piston 52 less effective.

The torque on the valve 16 has also been reduced but not in the same proportions as that on the piston 52 so it is still impossible to exceed the predetermined governor speed by manipulation of the carburetor throttle or choke.

It is to be observed the offset or unbalanced valve 16 is eccentrically mounted in the conduit 110a so that it is responsive to fuel mixture flow and tends to move by reason thereof into a closing direction.

Reference will be had to Figs. 4 to 9, inclusive, wherein a similarly but more complicated form of the invention is illustrated. In said figures, numerals of the 100 series similar to numerals previously utilized in the primary series, designate parts in this modification identical to or similar to parts designated by the primary series in Figs. 1 to 3, inclusive. In view of the marked similarity of the two forms of the invention, it is believed a description of the major portion of the invention shown in Figs. 4 to 7 is unnecessary. The showing, however, herein does show the parts with the valve—see Fig. 6—in what might be said to correspond to almost full open position. To this extent, Fig. 6 also is representative of the position parts of the invention shown in Figs. 1 to 3, inclusive, will assume when in that position. The present form of the invention, however, includes an auxiliary piston arrangement, to which reference will now be had.

In the present form of the invention the body portion 124 includes another cylinder 170 and mounted therein is an auxiliary piston 171 suitably recessed as at 172—see Fig. 8—to receive an auxiliary spring 173 which bears against one effective face of the piston and one effective face of the cylinder and normally constrains the auxiliary piston to the right—see Fig. 8. The piston has a stem portion 174 which mounts a valve member 175. The main power cylinder 151 includes a port 176 that provides communication between the cylinder 170 and cylinder 151. There is provided a passage 177 between the cylinder 170 and the exterior of the housing portion 124. This vents the auxiliary cylinder to the atmosphere. The size and force of the spring 173 may be as desired or required.

An adjustable member 171a is provided for adjusting the spring tension. This is similar to the adjustment 151a for the tension of the power spring 155. In this form of the invention, one end of the power piston 152 is subject to pressure in the conduit 110a and on the downstream side of the valve 16 by means of the port 161 and 162, these communicating by way of the chamber 129 closed by the cover 163 and sealed by the gasket 129a, the same being secured to the face of the wall 122 by bolts 163a, or the like.

The amount of resisting effort desired to oppose turning effort of the valve 116 through the lever 147 and roller 150 by reason of the engagement of the plunger carried by the piston 152, can be controlled by the area of said piston and the rate of the power piston spring 155 opposing the effort of the power piston 152. The outer end of the power piston 152 is subjected to atmospheric pressure through the port 177 controlled by the valve portion of the auxiliary piston 171. The auxiliary piston 171 is subject to the pressure on the upstream side of the valve 116 through the orifice or port 180, on one end to the atmospheric pressure through the port 171 on the other end.

The auxiliary spring 173 is calibrated to hold the piston 171 back against the cap 125, thereby keeping the port 177 open when the carburetor valve, not shown, is in the wide open position, so that the differential pressure in the conduit 110a and the atmospheric pressure is acting on the power piston 152 to resist the closing effort of valve 116 through the roller 150 attached to the lever 147 as the roller 150 contacts the end of the power plunger carried by the power piston 152.

The parts are in the position as shown in Fig. 4 when the carburetor valve—not shown—is in a wide open position and the governor is in charge of the engine, but when the carburetor valve—not shown—is moved toward the closed position and the pressure in the conduit 110a on the upstream side of the valve 116 has reached the predetermined amount to overcome the resistance of the auxiliary spring 173, the auxiliary piston 171 is moved to the position shown in Fig. 8 closing the atmospheric port 177 making the effort of the power piston 152 negative as it tends to oppose the closing effort of the valve 116 through the lever 147 and the roller 150. This is to compensate for the decrease in the turning effort of the valve 116 due to the change in the pressure and direction of the fuel mixture in the conduit 110a on the upstream side of the valve 116 caused by moving the carburetor valve—not shown—away from a full open position to a partially closed position. Without some compensating device, the selected set speed or predetermined governor speed could be exceeded by securing a proper positioning of the carburetor valve.

The piston 152, therefore, is responsive to differential pressure within the conduit 110a and the atmospheric pressure and said piston is arranged to oppose the closing effort of the valve 116 through the means shown herein so as to make the same effective over all or any part of the working range of the governor to assist in straightening out the force line as produced by the valve 116 and to reduce the governor speed if the force of this power piston 152 is reduced or made negative by closing the atmospheric vent or bleed 177, this power piston as previously stated, is subject to pressure within the conduit 110a on the downstream side of the governor valve and is also subject to atmospheric pressure.

The auxiliary piston 171 is subject to the pressure within the conduit 110a on the upstream side of the governor valve and is subjected also to atmospheric pressure. As previously stated, the force of this auxiliary piston is opposed by the calibrated spring 173, calibrated to hold this auxiliary piston in place until a predetermined vacuum or atmospheric pressure has been reached, which generally is just above the full

load governor speed and when the carburetor throttle is in a wide open position and when the governor valve 116 is in full control of the engine.

When the carburetor throttle valve—not shown—is moved toward a closed position, the pressure in the conduit on the upstream side of the governor valve 116 is lowered and at the pre-determined point, the auxiliary piston 171 will be moved into the position shown in Fig. 8 to close the atmospheric port or bleed 177, thereby rendering the power piston 152 inoperative. This is necessary to keep the governor speed from being exceeded as the closing effort or torque on the governor valve 116 has been reduced, due to the change in direction of flow and lowering of the pressure above or on the upstream side of the governor valve 116.

In Figs. 10 to 12, inclusive, there is illustrated a second basic embodiment of the invention. Numerals of the 200 series wherever possible, are employed to designate parts similar or identical to parts similarly designated by numerals of the primary or 100 series. Herein the invention is different, broadly speaking, in the following respects:

The specific type of anchorage for the sinusoidal faced member 239 is different. Likewise the specific shape of the sinusoidal surface thereof differs from that shown at 46 and 146 in Figs. 1 and 4, respectively, being less acute. The link 30 connected spring is differently anchored to its support. The link is sequentially connected to the power piston as distinguished from the pressure type contact previously described. The valve means is directly associated with said linkage 35 instead of being indirectly connected thereto, and more especially the valve means is of dual character and the power piston is directly exposed to the vacuum chamber. The cap structure on the end of the body portion is of a different form, and furthermore, the so-called power spring is omitted. The points of similarity will be obvious from an inspection of said figures, and in this respect also this form of the invention is similar to the simpler type shown in Figs. 1 to 3, inclusive, as distinguished from the form of the invention shown in Figs. 4 to 9, inclusive.

In this form of the invention, the spring anchoring member 237 is supported as at 231 by the eccentrically positioned member 236. This has a surface 237a engaged by the tail portion 240 of the cam member 239 mounted within the chamber 229 as at 238. The link structure 243 mounts the roller 245 having sinusoidal surface engagement and one end of the link structure 40 mounts the pin 242 connected to one end of the spring 241, the other end being connected as at 237b, the member 237 secured in adjusted position by the bolt 234 which extends through the threaded aperture 233 in the side wall 222 and has its head portion seated in the chamber 235 of the projecting boss portion 232.

The body portion 210 is provided with the bore portion 210a and the anchoring flanges 211, web connected as at 212, are provided with the openings 213 therethrough for usual adaptor type anchorage. The body portion includes the extension 224 in which is mounted the power piston 252. The end of the cylinder 251 which receives said power piston, is closed by the press fitted disc 225.

The tower piston is provided with a connecting rod 285 connected thereto as at 252a. The cylinder communicates with the passage 210a by means of the opening 253 and thus is subject to

the pressure at that point. The opposite face of the piston is subject to pressure of the fuel passage 210a by means of the ports 258, 259 and 260.

Positioned in the passage 210a is a partition 286 that extends longitudinally of the same, and the same is suitably slotted as at 287 to permit movement of link 288 therein. The link 288 is pivotally connected as at 289 to the bracket 290 also pivotally connected to the other end of the connecting rod 285 and said bracket is suitably secured as at 291 to a metallic resilient spring type vent or valve 292 suitably secured as at 293 to the lower end of the partition 286.

Another valve 294 of similar character, is similarly secured at its lower end as at 295 to the adjacent wall of the passage 210a and near its upper end mounts a bracket 296 which at 297 is pivotally connected to the other end of the link 288 and is connected also to one end of a link 298. The other end of said link 298 is pivotally connected at 299 to the link 243. In this instance, the resistance of the spring type valves cooperates with the other forces so that substantially the same result or broad type of operation is obtained with this type of governor as is obtained with the other generic type of governor represented by the two sub-generic forms illustrated in Figs. 1 to 3 and 4 to 9, inclusive.

In this third form of the invention, the sinusoidal faced member 239 includes a spring anchorage 282 which is a portion of the wall 221 and forming with a suitable gasket and cover structure, the latter being secured thereto by bolts or the like, applied to the tapped holes 223 for forming a closed and sealed chamber.

Wall 221 includes an eye anchor portion 282 which anchors one end of spring 283, the other end thereof being anchored as at 284 to the cam member 239. The sinusoidal faced member thus is always constrained into contact with the adjustable construction 231—236. In certain instances, if support 238 for member 239 is not of clamping character, closing movement of roller 245 will endeavor to tilt the member 239 which then will be opposed by the spring 283.

The instant form of the invention differs from that previously described in that instead of using a valve supported by a shaft associated with anti-friction means to keep friction within reasonable limits for satisfactory performance incident to operation due to the small turning effort produced by the offset or balanced valve means, the present valve means consists of two pieces of spring steel 292 and 294 as previously described and mounted and connected as described.

A relatively short movement of the linkage will close the conduit 210a. The stress on the valve means accordingly is relatively low and well within the elastic limits thereof. The arrangement is essentially a relatively frictionless control for the fuel flow. The valve means inherently includes a yielding arrangement so that the device is more sensitive or responsive to the varying pressures over any one predetermined portion of its travel than the last or remaining portion.

The valve construction can be so constructed that it will have a closing effort over part of the range of travel and a resisting effort over the remaining portion of its travel, with spring means to resist the closing effort of the valve means to any predetermined amount over its entire range of travel.

Reference will now be had to Figs. 13 to 15,

inclusive. Fig. 13 is a chart of three curves of one form of the invention. Curve A is for 1,500 R. P. M., Curve B for 2,000 R. P. M. and Curve C is for 2,500 R. P. M. Fig. 14 is a chart of three curves of the same engine at the three governed speeds for corresponding valve positions, the other coordinate being the corresponding vacuum in inches of mercury. These curves are double lettered. From a comparison it is noted the low speed curve at small degree valve positioning has a marked sag from the points between 10 and 30 degrees. This sag is less pronounced in the intermediate speed curve and is very slight in the highest speed curve. In other words, the invention curves may be said to substantially correspond to the vacuum curves for the same speeds. This means the invention is approximately isochronous with the engine.

Comparison of curves on chart, Fig. 15, with curves on chart, Fig. 14, shows that the same do not correspondingly conform. The low speed curve AAA does not sag as much as curve AA and the high speed curve CCC sags more than curve CC. The same may also be said as to curve BBB relative to curve BB. So that these curves of nonadjustable prior art devices are quite different from the vacuum curves for the same speeds and valve position.

As illustrated in Fig. 15, the prior art basic curve is unmodified vertically for each governed speed. As shown in Fig. 14, the force required to oppose the engine vacuum at different speeds varies for different valve positionings and the corresponding curves are not substantially the same curve correspondingly shifted but are curves progressively flattened from low to high speed. Chart Fig. 13 also is of the latter character. These curves visually demonstrate that the present adjustable cam invention more closely corresponds to the engine vacuum-corresponding speed condition curves for like valve positionings.

In other words, in prior art devices it is required to employ different cams for different engine speeds, whereas with the present invention one relatively stationary sinusoidal surfaced member can properly function for substantially all engine speeds. In the prior art devices the cams are designed to extend the spring or increase the resistance a given amount for each degree of valve movement and this ratio is maintained at all engine speeds as the speed is raised or lowered by adjusting the spring only.

The function of the sinusoidal surfaced member in this invention is different for different engine speeds as the ratio of acceleration of the spring to degree of valve movement is changed as the sinusoidal surfaced member position is changed with the spring adjustment to secure different engine speeds to more nearly conform to the resisting effort or force curves desired to secure satisfactory performance at various speeds with the same mechanical set-up or specification.

These charts and the foregoing description relative thereto is set forth for the benefit of those not especially highly skilled in this art, since the advantages of the spring accelerating means in the present invention will not be so readily apparent to those last mentioned.

In order to increase the efficiency of the governor the parts may be anti-frictionally connected as illustrated in Figs. 16 to 19. Thus maximum power can be obtained from the piston at wide open position of the control valve means.

In these figures numerals of the four hundred

series indicate parts identical or similar to parts illustrated in Figs. 1 and 2 and indicated therein by corresponding numerals of the primary series.

In these figures the sinusoidal surfaced member engaging roller 445 is shown carried by T-shaped links 443 which at one end straddle the lever arm 447 and are connected thereto as at 448. Such connection is of anti-friction character, as broadly indicated in Fig. 19. It is similar to the anti-friction connection indicated at 444^a in Fig. 16. Member 444 forms the link connection and sinusoidal surfaced member engaging roller pivot. The other ends of the links 443 are connected by member 442 which constitutes the spring anchorage.

The lever 447 herein, however, includes a slot 414^a to receive a correspondingly formed end of shaft 414. Herein the arm 447 is extended as at 447^b and a counterweight 447^c, which may be adjustably weighted, is secured thereto as at 447^d. Arm 447 may include stop portion 447^a. This limits the arm travel in the counter-clockwise direction, see Fig. 16, by engaging the lower link 443.

The piston engaging roller 450 is carried by arm 447 as shown in Figs. 16 to 19, inclusive. Such mounting includes the pin 449 extending through sleeve 449^a engaged at opposite ends by washers 449^b which cover central aperture 450^a in roller 450. Between the roller and sleeve and the washers are the anti-friction balls 450^b.

The several forms of the invention previously described may be similarly constructed without departing from the broad features of the invention. Fig. 16, however, does illustrate an arm which by experiment so far has been determined to give most satisfactory results. If the longitudinal axis of slot 414 be extended and radii be projected through the slot center and the axes of 448 and 449, it has been found that if 448 lies approximately 42½° from the longitudinal axis described and 449 lies approximately 45° therefrom in the opposite direction, best results will be obtained. This manufacturing data is supplied for completeness of disclosure.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A governor for internal combustion engines including fuel supply passage means; eccentrically pivoted valve means therein, a relatively stationary sinusoidal surfaced member, a link type follower therefor, spring means normally constraining the link and follower toward open valve position, a cylinder, and piston means in said cylinder subject to differential pressure in the passage and operable to actuate said valve means in opposition to said spring means.

2. A governor as defined by claim 1 characterized by the addition of an adjustable support for the sinusoidal surfaced member and an adjustable anchorage for the spring means, said sinusoidal surfaced member and anchorage having cooperating engagement, and a single means for simultaneously adjusting the sinusoidal surfaced

member position, and the spring means initial tension.

3. A governor as defined by claim 1, characterized by the addition of an auxiliary piston and cylinder for the first mentioned piston control.

4. A governor as defined by claim 1 characterized by the addition of an auxiliary piston and cylinder for the first mentioned piston control, said valve means being of multiple character.

5. A governor as defined by claim 1 characterized by the addition of a lever arm for valve means operation, said link means being connected thereto and the piston having operative connection with said arm, and by the addition of means normally constraining the piston toward a position corresponding to closed valve position.

6. A governor as defined by claim 1 characterized by the addition of a lever arm for valve means operation, said link means being connected thereto and the piston having operative connection with said arm, and means normally constraining the piston toward a position corresponding to closed valve position, an adjustable support for the sinusoidal surfaced member and an adjustable anchorage for the spring means, said sinusoidal surfaced member and anchorage having cooperating engagement, and a single means for simultaneously adjusting the sinusoidal surfaced member position and the spring means initial tension.

7. A governor as defined by claim 1 characterized by the addition of a lever arm for valve means operation, said link means being connected thereto and the piston having operative connection with said arm, and means normally constraining the piston toward a position corresponding to closed valve position, and a roller carried by the arm and engaged by the piston.

8. In a governor for internal combustion engines and the like, the combination with a fuel supply passage therethrough, valve means in the passage and spring means normally constraining the valve means toward open position, of a stationary sinusoidal surfaced member, a follower operatively connected to the valve means, the movement of the follower being controlled by the stationary member and spring means, said follower being constrained by the spring means into sinusoidal surface engagement, and a passage suction operable piston operatively associated with the valve means.

9. A governor as defined by claim 8 characterized by the addition of an adjustable anchorage for the spring means, an adjustable support for the sinusoidal surface member, and a single means for simultaneously and conjointly adjusting the spring tension, the spring position and the operative position of the sinusoidal surface member.

10. A governor as defined by claim 8, characterized by the addition of an auxiliary piston and cylinder for first mentioned piston control.

11. In a governor structure, the combination of a suction responsive valve shaft, an arm rigid therewith, an operating roller carried thereby, a link structure having one end pivoted thereto and having a yielding opposite connection, and a follower pivotally supported by the arm, and approximately $87\frac{1}{2}^\circ$ from the operating roller connection thereto.

12. In a governor structure, the combination of a suction responsive valve shaft, an arm rigid

therewith, an operating roller carried thereby, a link structure having one end pivoted thereto and having a yielding opposite connection, a follower pivotally supported by the arm, and a link engageable stop carried by the arm.

13. In a governor structure, the combination of a suction responsive valve shaft, an arm rigid therewith, an operating roller carried thereby, a link structure having one end pivoted thereto and having a yielding opposite connection, a follower pivotally supported by the arm, and approximately $87\frac{1}{2}^\circ$ from the operating roller connection thereto, and a link engageable stop carried by the arm.

14. In a governor for internal combustion engines and the like, the combination with a fuel supply passage therethrough, valve means in the passage and movable toward closed position by fluid flow operating directly thereon, spring means normally constraining the valve means toward open position, a connection between the spring means and the valve means, and a passage differential pressure operable piston operatively associated with the valve means and normally constraining the valve means toward open position.

15. In a fluid operable governor for internal combustion engines, a housing structure including a fuel passage therethrough, and a control valve therein and movable toward closed position by fluid flow operating directly thereon, means connected to the valve for valve operation, other means responsive to fluid pressures upon opposite sides of the valve, and cooperating with the first mentioned means for valve control, and two passage forming means formed entirely within the housing structure providing communication between the fuel passage at opposite sides of the valve and the second mentioned means whereby the fluid medium operative upon the second mentioned means is no dirtier than that in the fuel passage.

16. In a fluid operating governor for an internal combustion engine provided with a fuel conduit and valve means adapted to control the flow of fluid fuel in said conduit and movable toward closed position by fluid flow operating directly thereon, the combination of means responsive to pressure within said conduit, and means forming independent passages communicating with said conduit to control said pressure responsive means, one of said passages being subject to the pressure on the engine side of said valve means and one of said passages being subject to the pressure on the atmospheric side of said valve means to supply said passage forming means with clean air to control the fuel supply that is passing through said governor conduit.

17. In a differential pressure governor for an internal combustion engine having a throttle, the combination with an intake, an unbalanced governor valve therein always constrained toward open valve position, of a pressure responsive means responsive to the differential effect of the suction in the intake at opposite sides of the valve and normally constraining said valve toward open position at all times, said means being arranged for diminishing its constraint upon said valve in accordance with closing movement of the throttle from the wide open position.

18. A governor as defined by claim 17, characterized by the differential pressure responsive means having opposite faces subject to different pressures.

19. A governor as defined by claim 17, char-

acterized by the differential pressure responsive means having opposite faces subject to different pressures, and being of piston character.

20. In a differential pressure governor for an internal combustion engine having a throttle, the combination with an intake, an unbalanced governor valve therein always constrained toward open valve position, of a pressure responsive means responsive to the differential effect of the suction in the intake at opposite sides of the valve and normally constraining said valve toward open position at all times, said means being arranged

for diminishing its constraint upon said valve in accordance with closing movement of the throttle from the wide open position, the governor valve in closing having an increasing torque incident to fuel flow in the intake, and said pressure responsive means having a corresponding increasing compensating effect incident to the corresponding differential pressure change due to the movement of the governor valve toward closing position.

RAYMOND HUFFORD.
